US0D1109800S

(12) **United States Design Patent** (10) **Patent No.:** **US D1,109,800 S**
(45) **Date of Patent:** **** Jan. 20, 2026**

(54) **COPYING MACHINE**

(71) Applicant: **Sharp Kabushiki Kaisha**, Sakai (JP)

(72) Inventors: **Atsushi Kaseno**, Osaka (JP); **Takayuki Tsutsui**, Osaka (JP)

(73) Assignee: **SHARP KABUSHIKI KAISHA**, Sakai (JP)

(**) Term: **15 Years**

(21) Appl. No.: **29/956,899**

(22) Filed: **Aug. 9, 2024**

(30) **Foreign Application Priority Data**

Feb. 15, 2024 (JP) ..... 2024-003122 D
(51) **LOC (15) Cl.** **14-02**
(52) **U.S. Cl.**
USPC **D18/55**
(58) **Field of Classification Search**

(57) **CLAIM**

The ornamental design for a copying machine as shown and described.

DESCRIPTION

FIG. 1 is a front, top, right, perspective view of a copying machine in accordance with our new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a right side elevation view thereof;

FIG. 7 is a left side elevation view thereof;

FIG. 8 is a rear, top, right perspective view thereof; and,

FIG. 9 is a rear, bottom, left, rear perspective view thereof. The broken lines in drawings show portions of the copying machine that form no part of the claimed design.

1 Claim, 9 Drawing Sheets
